UNITED STATES PATENT OFFICE.

IRA J. BABCOCK, OF NEW YORK, N. Y.

LOCK.

SPECIFICATION forming part of Letters Patent No. 615,206, dated November 29, 1898.

Application filed December 29, 1897. Serial No. 664,174. (No model.)

To all whom it may concern:

Be it known that I, IRA J. BABCOCK, a citizen of the United States, and a resident of the city of New York, (Brooklyn,) county of 5 Kings, State of New York, have invented certain new and useful Improvements in Locks, of which the following is a specification.

This invention relates to improvements in key combination-locks of the type known as 10 "locking-bar" locks, wherein a series of independently-movable tumblers are arranged in combination with a locking-bar in such manner that the tumblers may be locked, through the coöperation of the locking-bar, 15 in practically as many combinations as there are different mathematical combinations possible from a number of things equal to the total number of tumblers. In such locks there may be as many different keys as there 20 are possible locking combinations of tumblers, and only that key which locked the tumblers or its exact duplicate can open the lock. In such locks it is indispensable that the locking combination shall not reveal it- 25 self to delicate feeling with a pick and shall not permit an impression to be obtained of such combination, and it is the purpose of this invention to prevent both the picking of the lock and the obtaining of an impression 30 and also to allow the lock to be locked in both directions.

To safeguard the lock, it is necessary that every tumbler, whether locked or unlocked, shall have exactly the same degree and ease 35 of motion, shall feel exactly the same to a pick, and give the same impression on a blank as every other tumbler; but heretofore these results have not been properly attained, because pins have been heretofore employed to 40 limit the motions of the tumblers, and springs have been used to compel the tumblers and locking-bar to go to the full limit of their throws. The result has been that when some 45 combination of tumblers has been locked and an attempt has been made to feel out the combination some of the tumblers would be moved up against the limiting-pins and others against the locking-bar, and a very delicate touch could sometimes detect the difference, 50 and thus finally work out the combination; or if a blank were inserted it would some-

times be possible to get an impression of the locking combination, owing to the different elasticity of the pins and locking-bar, aided by the springs. It is also practically impossible in manufacturing the locks to attain such perfection that the tumblers will bring up in the same manner on two different parts, and the difference might be sufficient to permit feeling out the combination. The use of 60 stop-pins, moreover, prevents allowing the tumblers to be moved from the neutral or unlocked position in both directions in locking, and one of the especial advantages of the present invention is that it does not permit of constructing locks in which the tumblers can be locked in both directions, such a 65 double-locking lock being hereinafter shown and described.

Therefore this invention consists, broadly, 70 in the combination of the locking-bar and independently-movable tumblers so constructed and so arranged in coöperation with each other that the locking-bar equally limits the movement of all the tumblers both in 75 the locked and the unlocked positions when the effort is made to open the lock and without any springs or pins. Thus in the attempt to open the lock with a pick every tumbler comes up against the same locking-bar and 80 with the same degree and kind of motion, and no difference of feeling is perceived, nor can an impression of the locking combination be obtained, for both the locked and the unlocked tumblers are equally free to move 85 within the small limits imposed by the locking-bar, and all can be turned indifferently a little this way or that without any resistance of springs or other parts.

Mechanically the invention broadly consists in the combination of a rotatable locking-bar and independently-movable tumblers, each of which has an exactly similar projection for rotating the locking-bar and other similar projections adapted to engage on the 95 locking-bar and limit the play of the tumblers.

The essence of the invention is applicable to any key combination-lock of the locking-bar type, and I therefore show on the drawings and describe in the specification its application to several locks. I also hereinafter

fully describe in detail the construction of one of said locks which includes several subsidiary inventions which I claim in this application. I do not, however, fully describe 5 the details of the other locks, since they include inventions which I particularly describe and especially claim in other pending applications.

Referring to the drawings which accompany 10 the specification, Figure 1 is a sectional elevation of the invention applied to a padlock and showing the shackle locked. Fig. 2 is a horizontal section of the same as seen from below; and Fig. 3 is a similar section of the 15 same parts, but in the unlocked position. Fig. 4 is a view from below, but on large scale, showing certain tumblers and the locking-bar in locked position. The shaded projections 5 6 indicate the tumblers which are 20 in the locked position. Fig. 5 is a similar view showing all the tumblers and locking-bar in the unlocked position. Fig. 6 is a diagram illustrating the spacing of the projections of the tumblers. Figs. 7 and 8 are plan 25 views of the lever which locks and releases the tumbler-case which contains the tumblers, locking-bar, and other parts through the agency of the locking-bar in the locked and unlocked positions, respectively. Fig. 9 is a 30 plan of a washer. Figs. 10 and 11 illustrate two several keys. Fig. 12 is a section, on large scale, of the invention applied to a cylinder-lock which is arranged to lock in both directions and showing the tumblers and 35 locking-bar in the unlocked position. Fig. 13 is a similar section, but showing the locking-bar and certain of the tumblers in a locked position. The shaded projection indicates the locked tumblers. The stationary case in 40 this figure is slightly turned from the position in which it is shown in Fig. 12. Fig. 14 is a section on the line 14 14 of Fig. 13 and showing the parts in the locked position. Fig. 15 is a diagrammatic plan, and Fig. 16 an edge 45 view, of one of the tumblers, illustrating the spacing of the projections. Fig. 17 is a plan, and Fig. 18 an edge view, of a washer. Fig. 19 is a side view, partly sectioned, of a lock equipped with sliding tumblers. The parts 50 are in the unlocked position. Fig. 20 is a similar view, but showing the locking-bar and certain of the tumblers in the locked position. The locked tumblers are indicated by the shading. Fig. 21 is a plan of a washer. Fig. 55 22 is a side view, partly sectioned, of sliding tumblers and a locking-bar adapted to lock in both directions.

Referring to that form of lock shown in Figs. 1 to 8, A is the case of a padlock, B the 60 shackle, and b the socket therein to be engaged by the bolt. The tumblers are assembled between the bottom plate C and the top plate D, which are positioned the proper distance apart by the shield II and fixed by rivets on 65 said shield and by the axial pin f of the tumblers F. Said plates C D, when connected

together as described, constitute what I term the "tumbler-case." E is the key-barrel, which may be a cylinder slotted for the passage of the key, the slot being open on one 70 side to permit the bits of any key K to project to engage the tumblers in the manner hereinafter described. A longitudinal rib e² on said barrel E serves to move the tumblers to the full limit of their throw both in locking and unlocking. Said key-barrel is the axis around which the tumbler-case rotates in locking and unlocking and is also provided with necks e' e'', which have a working fit through plates C D, and neck e comes flush 80 with the outside of case A when the lock is assembled, neck e' having a working fit and being movably held in a socket in the top A', which carries the shackle B. The locking-bar G, pivoted in plates C D, is constructed 85 and operates as hereinafter described. The bolt D' is formed as a part of or fixed on said plate D and in the locked position enters socket b of shackle B, thereby locking said shackle. As the lock unlocks the tumbler-case rotates to the position of Fig. 3, withdrawing bolt D' from socket b, and permits the shackle to be raised and turned in the usual manner.

There may be any desired number of tumblers F, each capable of independent rotation, and between each pair of tumblers is a stationary washer L. Each washer is of thin metal, preferably shaped as shown in Fig. 9 and provided with a hole l, which fits on the 100 pin f, and with projections l' on the end adjacent to shield II, so that said washers are held stationary by engaging said shield. Said projections l' are spaced so as to allow of the free sweep of the bits of the key. Each of 105 said tumblers F is provided on the side adjacent to said shield II with a true-key slot 1 and false-key slots 2 3, each spaced on opposite sides of said slot 1 an angular distance equal to the angular revolution of the tumblers. On the side adjacent to the tumblers the said shield II is cut away sufficiently for the ready insertion and sweep of the key in locking and unlocking, and therefore whatever tumblers are locked or unlocked there 110 will always be two lines of recesses at the open side of said shield II, and said recesses will not indicate what tumblers are in either position. Said shield II will also prevent a pick from reaching by to feel the third 115 recess and also from reaching the locking-bar G. On the side opposite to said shield II and adjacent to said locking-bar G each of said tumblers F is provided with projections 5, 6, and 7, projection 6 in particular serving 120 to rotate the locking-bar G from the locked to the unlocked position and the reverse and also in certain circumstances serving, like projections 5 and 7, to prevent rotating the tumblers by engaging on the locking-bar, as 125 will be hereinafter explained. The surfaces 9 10 11 of said projections 5 6 7, respectively,

are preferably shaped on arcs of circles such that when either projection is against the locking-bar, as in Figs. 4 and 5, said arcs are parallel to the peripheral curve of said locking-bar G—that is to say, they then coincide with arcs of circles struck from the axis of the said locking-bar as a center. Fig. 5 makes this clear as to projections 6 and 7, and the same is true of surface 9 of projection 5. The 10 distance of projections 5 and 7 from projection 6 is such that if lines $x y z$, Fig. 6, are drawn from the axis of the tumbler to the points where said arcs 9 10 11 intersect the outer ends, respectively, of projections 5 6 7 15 the angle between any two adjacent lines, as $x y$ or $y z$, will be equal to the angular movement of the tumbler in locking or unlocking, and the width of the ends of projections 6 and 7 is sufficient to interfere with said locking-bar G if an attempt is made to surreptitiously open the lock. Said locking-bar G, pivoted in said plates as said, is sufficiently long to extend across the edge of all the assembled tumblers, Fig. 1, and is preferably shaped in 20 cross-section, as shown. Said locking-bar is provided with arms or ribs 15 16, separated by a slot or groove 17, which extends the whole length of said locking-bar and in which the projection 6 works somewhat like the 25 tooth of a gear, the coaction of the tumblers and locking-bar resembling that of a gear and pinion. Said arm 15 of the locking-bar is preferably hammer-shaped in cross-section, as shown.

30 On the end of locking-bar G, adjacent to the cap A', is a cam 20, which engages in a recess or talon 21 of a plate-lever 22, pivoted on the pin f. Said lever 22 is provided with a hook 24, adapted to engage on the end of 35 said cam 20 when locking-bar G is in the locked position, Fig. 2, and prevent the said locking-bar from turning too far, and is also provided with a hook 26, which is bent at right angles to the plane of said plate-lever 22 and works in a curved slot 27 in the cap A'. At the end of said slot 27, adjacent to the position of hook 26 when the lock is locked, is a recess 28, into which said hook 26 is moved by the locking-bar to prevent turning the 40 tumbler-case to the unlocked position until the lock is unlocked.

45 The lock is operated as follows: Suppose it to be unlocked, all the tumblers F and the locking-bar G being in the positions of Fig. 5, the tumbler-case in the position of Fig. 3, and the bolt D' withdrawn from the socket in shackle B. Now a key having a combination of bits 30 31 22, corresponding to some 50 combination of tumblers, is inserted and turned in the direction of the arrow, Fig. 5. Said bits 30 31 32 engaging in the true-key recesses 1 of the said tumblers, the tumbler-case turns to the position of Fig. 2, wherein bolt D' enters socket b in shackle B, and further motion of the tumbler-case as a whole 55 being prevented by said hook 26 the key turns said tumblers to the locked position of

Figs. 2 and 4. While so turning, the projections of each of the tumblers in the locking combination have engaged on the locking-arm 15 of locking-bar G and turned said locking-bar to the locked position of Figs. 2 and 70 4, wherein said arm 15 just clears the projection 6 of said locking-tumblers, the rounded periphery of said locking-bar meantime 75 sweeping freely by the surfaces 10 and 11 of the projections 6 and 7 of the tumblers which were not moved by the key. As the locking-bar turns its cam 20 turns lever 22, so that the hook 26 comes into the recess 28 and prevents turning back the works to withdraw the bolt from the shackle, and hook 24 prevents turning the locking-bar too far. As the tumblers come to the limit of their movement, which is determined by projections 5 80 85 coming against the periphery of the locking-bar, the bits of the key pass out of the recesses in said tumblers and the key continues turning, the rib e² of barrel E entering the recesses 3 of such tumblers as were locked 90 and the recesses 1 of such as remained unlocked and lining all up just as the key turns to the full end of its motion. The lock is now locked and the key may be withdrawn. To unlock, the same key as locked or the exact 95 duplicate thereof is inserted and turned in the reverse direction to that of locking. Its bits engaging the slots 1 of such tumblers as were locked turn same back to the unlocked position, the projections 6 of such 100 tumblers engaging arm 16 of locking-bar G and turning it back to the unlocked position. As the locking-bar turns its cam 20, engaging lever 22, moves hook 26 out of recess 28, and the continued pressure on the key rotates the tumbler-case as a whole back to the unlocked position, hook 26 now moving freely 105 back through slot 27. At the final movement of the key rib e² on barrel E, engaging in slots 2 of all the tumblers, lines all up. 110 The lock is now unlocked.

Suppose when the lock is locked an effort is made to open the lock with a false key having some bits, among others, which will engage some of the unlocked tumblers. Then the projections 7 of such tumblers will move so as to be engaged by arm 15 of locking-bar and prevent same from turning back to the unlocked position.

Suppose an effort is made to feel out the 120 combination with a pick. Then since all the tumblers, whether locked or unlocked, have their motions limited by the locking-bar G and the free play of all is equal in all directions there is no indication of what tumblers 125 are locked or unlocked. Also if the pick moves any unlocked tumbler as far as it will go toward the unlocking position its projection 7, being engaged by arm 15 of locking-bar G as the locking-bar begins to move, will 130 prevent said locking-bar from turning to the unlocked position.

If an effort is made to obtain an impression of the combination, all the tumblers being

equally free to move all will make the same impression in the blank, and no indication of the combination will be given.

Referring to Figs. 12 to 16, which show the principal features of the invention applied to a cylinder-lock, S is the external fixed case; T, the internal rotatable cylinder or tumbler case; F', the annular tumblers, and G' the locking-bar. Said tumblers and locking-bar are now shown constructed and arranged to lock in both directions; but I do not herein claim said construction specifically, since the same is fully described and claimed in another of my applications pending in the Patent Office, nor do I herein show or describe all the minor details of construction, since said figures are shown only to indicate how the principle of arranging the locking-bar and tumblers so that the locking-bar shall limit the motion of the tumblers without requiring any stop-pins or springs is applied to cylinder-locks. Each of said tumblers F' is provided with two projections 40 41, which are adapted to rotate the locking-bar in locking and unlocking in one or the other direction, and with two surfaces 42 43, which are also in effect projections and are adapted to limit the motion of the tumblers when in the locked position by engaging with the locking-bar. As shown, said tumblers are practically circles, with the spaces between said surfaces 42 43 and projections 40 41 cut away, the ends of said projections being on the same arc as the general periphery of the tumblers. The surfaces 45 46 47 48 of said projections are preferably shaped on arcs of circles in the manner described in connection with the tumblers of the padlock. Said tumblers center and turn easily within the tumbler-case T, and around the central orifice of each tumbler is a number of recesses 50 51 52 53 54 55 56 57, all spaced an angular distance apart equal to the angular rotation of the tumblers. Slot 50 serves as the true-key slot and the others to conceal the relative position of the tumblers, since whether any tumbler is locked or unlocked there is always presented to the key-hole the same number of lines of slots. Said locking-bar G' is now provided with three arms 60 61 62. Said arm 60 has two hammer-shaped surfaces, as shown, one of which will just clear said projection 40 in one locked position, and the other of which will just clear said projection 41 in the other locked position. The back 64 of said locking-bar is preferably shaped on an arc struck from the axis of the tumbler-case T as a center and is positioned so that when the locking-bar is unlocked it will pass freely by the inner wall of the fixed case S, but that when the locking-bar is locked one of its edges will enter one or the other recesses 68 69 in the said case S, and thereby prevent turning the tumbler-case T, which latter will be operatively connected with a bolt in any suitable manner. Between each pair of tumblers is an annular washer 70, of thin metal, preferably circular in shape,

with projections 71 72, which enter recesses 74 75 in case T and hold the washers stationary. The orifice in the center of each washer 70 is large enough to permit of the free insertion and sweep of the key X'. A key-barrel can of course be used, but I prefer dispensing with it and using a key which has a cylindrical shank 76, equipped with the desired combination of bits on one side. A stop-pin 78, (or equivalent device,) working in a circular groove in the tumbler-case T, limits the motion of said case.

In operation the parts being in the unlocked position of Fig. 12 the desired key being inserted engages in the key-recesses 50 of some combination of tumblers. As the key turns to the locked position of Fig. 13 it first revolves the tumbler-case T until the locking-bar G' comes opposite recess 68, and then the projections 41 of the locking-tumblers, engaging on the corresponding surface of arm 60 of locking-bar G', rotate said locking-bar to the locked position, in which one edge thereof enters said recess 68, and the ends of said projections 40 of the locking-tumblers prevent the locking-bar from turning out of said recess 68 to free case T until the same key or its exact duplicate has been inserted in the lock and turned in the reverse direction, restoring the parts to the unlocked position. Similarly, if, the works being unlocked, the key has been turned in the other direction it would have locked the tumbler-case in that direction, the edge of the locking-bar turning up into recess 69.

Referring to Figs. 19, 20, and 21, U is the tumbler-case, which will be placed in an outer case. (Not shown.) F² are the sliding tumblers, and G² the locking-bar, which is similar to that shown in connection with the padlock; but, as will be understood by those versed in the art, a locking-bar similar to that shown in Figs. 12 and 13 and arranged to lock both ways can be used with the sliding tumblers by providing the proper arrangement of projections on said tumblers, and such a locking-bar, in combination with sliding tumblers, is shown in Fig. 22. True-key recesses 80 and false-key recesses 81 82 are provided in the outer edges of each tumbler and spaced equally apart a distance equal to the throw of the tumblers, 83 being a shield around the key. On the edge adjacent to locking-bar G² each tumbler has a projection 85, adapted to rotate the said locking-bar, and also has surfaces 86 87, which are practically projections on opposite sides of said projection 85 and at a distance therefrom equal to the throw of the tumblers. The surfaces 88 89 90 of said projections are preferably shaped on arcs of circles, as hereinbefore described in connection with the rotating tumblers. Between each pair of tumblers is a washer 92, preferably shaped as shown and of thin metal and provided with projections 93 94, which enter spaces 96 97 in case U and hold the washers stationary, said washers also being cut out

on the opposite side, as at 98, to permit of insertion and the free sweep of the key.

Supposing the parts unlocked and in the position of Fig. 19, a key being inserted and turned will shift some combination of tumblers to the position of Fig. 20, rotating the locking-bar G² to that position in which it locks the tumblers, as hereinbefore described, only the key which locked or its exact duplicate being able to open the lock.

Referring to the aforesaid Fig. 22, the locking-bar G³ is similar in shape and construction to the locking-bar G' of Figs. 12 and 13. The tumblers F³, shaped as shown, are provided with the projections 104 and 105 to move the locking-bar in the one or the other direction and with the projections 106 107 to limit the extreme motions of the tumblers by bringing up on the locking-bar. True-key slots 100 101 and false-key slots 102 103 are formed in the other edge of each tumbler, so that whatever may be the positions of the tumblers two straight lines of slots will be accessible from the keyhole and no indication of the position of any tumbler will be given.

The projections of the sliding tumblers, as well as those of the cylinder-lock, in combination with the locking-bar, permit of dispensing with all springs and stop-pins and insure the security and other advantages hereinbefore enumerated.

Now, having described my improvements, I claim as my invention—

1. The combination in a key combination-lock of a series of independently-movable tumblers and a locking-bar adapted to be actuated by such tumblers as move and to limit the play of all said tumblers both in the locked and unlocked positions thereof, substantially as described.

2. The combination in a key combination-lock of a rotatable locking-bar and a series of independently-movable tumblers each of which has a projection adapted to rotate said locking-bar and other projections adapted to engage with said locking-bar and limit the motions of said tumblers, substantially as described.

3. The combination in a key combination-lock of a rotatable locking-bar, a series of independently-movable tumblers each having a projection adapted to rotate said locking-bar and other projections adapted to engage with said locking-bar and limit the motion of said tumblers, a key, a key-barrel therefor and a projection thereon adapted to move said tumblers to the extreme limit of their throw, substantially as described.

4. The combination in a key combination-lock, of a rotatable locking-bar, a series of independently-movable tumblers adapted to engage therewith, and a lever adapted to be moved by said locking-bar and to lock and release the tumbler-case, substantially as described.

5. In a key combination-lock, an oscillating tumbler-case carrying a locking-bolt and equipped with a rotatable locking-bar and independently-movable tumblers adapted to engage with the locking-bar, and a lever adapted to be moved by said locking-bar and in one position to lock said tumbler-case and in the other position to release the same, substantially as described. 70

6. In a key combination-lock, an oscillating tumbler-case carrying a locking-bolt and equipped with a rotatable locking-bar and independently-rotatable tumblers adapted to engage with the locking-bar, a recess in the lock-case, a lever adapted to be actuated by said locking-bar so as to enter said recess and lock the tumbler-case in one position and be free from said recess in the other position, substantially as described. 80

7. In a key combination-lock the combination of a rotatable locking-bar, independently-movable tumblers adapted to engage therewith, and a lever adapted to be engaged by said locking-bar and limit the motion thereof, substantially as described. 90

8. The combination in a lock of a rotatable locking-bar provided with arms separated by a groove, independently-rotatable tumblers having true and false key slots equally spaced, 95 and also having a projection adapted to engage said arms and move said locking-bar and other projections equally spaced on opposite sides of said first-named projection and adapted to engage with said locking-bar and limit the motion of said tumblers, substantially as described. 100

9. The combination in a key combination-lock, of a rotatable locking-bar, a series of independently-rotatable tumblers adapted to engage with said locking-bar and provided with true and false key slots equally spaced, a shield adjacent to and open toward said tumblers, a key, and a barrel therefor provided with a projection which is adapted to bring all the tumblers up to the limit of their throw, substantially as described. 105

10. The combination in a key combination-lock, of independently-movable tumblers, a locking-bar engaged by the tumblers and adapted to hold said tumblers in the locked or unlocked position, a cam on said locking-bar, and means adapted to engage said cam and hold said locking-bar in its operative position, substantially as described. 115

11. The combination in a key combination-lock, of independently-movable tumblers and a locking-bar adapted to mutually limit their respective motions without pins or springs, a cam on said locking-bar, a lever adapted to engage with said cam and to hold said locking-bar in operative position, and a slot in the case adapted to lock said lever in one position and release it in another, substantially as described. 125

12. The combination in a lock of independently-movable tumblers and rotatable lock-

ing-bar engaging therewith, and a lever adapted to be moved by said locking-bar, and said tumblers, locking-bar and lever being adapted to limit the motions of the tumblers and locking-bar without springs or pins, substantially as described.

In testimony that I claim the foregoing as

my invention I have signed my name, in presence of two witnesses, this 28th day of December, 1897.

IRA J. BABCOCK.

Witnesses:

REUBEN SHOLTZ,
BERNARD J. ISECKE.

Correction in Letters Patent No. 615,206.

It is hereby certified that in Letters Patent No. 615,206, granted November 29, 1898, upon the application of Ira J. Babcock, of New York, N. Y., for an improvement in "Locks," an error appears in the printed specification requiring correction, as follows: In line 65, page 1, the word "not" should be stricken out; and that the said Letters Patent should be read with this correction therein that the same may conform to the record of the case in the Patent Office.

Signed, countersigned, and sealed this 13th day of December, A. D., 1898.

[SEAL.]

WEBSTER DAVIS,
Assistant Secretary of the Interior.

Countersigned:

C. H. DUELL,
Commissioner of Patents.
